Primary Examiner — Michael C Stout*Assistant Examiner* — Eric Eldone Tormanen(74) *Attorney, Agent, or Firm* — ArentFox Schiff LLP(57) **CLAIM**

The ornamental design for an electrode, as shown and described.

DESCRIPTION

FIG. 1 is a perspective view of an electrode showing my new design;

FIG. 2 is a front view of the electrode shown in FIG. 1;
 FIG. 3 is a rear view of the electrode shown in FIG. 1;
 FIG. 4 is a left side view of the electrode shown in FIG. 1;
 FIG. 5 is a right side view of the electrode shown in FIG. 1;
 FIG. 6 is a top view of the electrode shown in FIG. 1; and,
 FIG. 7 is a bottom view of the electrode shown in FIG. 1.
 The broken lines in the drawings form no part of the claimed design.

1 Claim, 7 Drawing Sheets(56)
